UNITED STATES PATENT OFFICE.

WILLIAM G. WILLIAMS, OF ELGIN, ILLINOIS.

CHIROPRACTIC TABLE.

1,399,419.

Specification of Letters Patent.

Patented Dec. 6, 1921.

Application filed December 11, 1920. Serial No. 429,962.

To all whom it may concern:

Be it known that I, WILLIAM G. WILLIAMS, a citizen of the United States, residing at Elgin, in the county of Kane and

5 State of Illinois, have invented certain new and useful Improvements in Chiropractic Tables; and I hereby declare that the following is a full, clear, and exact description thereof, reference being had to the accompanying drawings, which form part of this

10 specification.

This invention is an improvement in chiropractic tables of the type shown in my Patent No. 1,269,354, dated June 11, 1918, and

15 whereon the patient can be comfortably lowered from a standing to a horizontal position when being placed upon the table, and can be raised to a vertical position after being operated upon.

20 The invention provides novel means for raising the table frame when a patient is to be placed thereon, and for cushioning the lowering of the table frame with a patient thereon; to provide novel means whereby

25 the tension of the springs for raising and for cushioning the lowering of the table frame can be regulated; to provide auxiliary spring means to operate when the table frame is being lowered with a patient and

30 for automatically throwing such spring means out of action when the table frame is nearly completely raised; to provide novel means for adjusting the abdominal supporting cushion whereby the same may be either

35 held rigid or can be yieldingly supported with more or less resistance by suitable springs; to provide novel means for adjusting the leg cushion; to provide novel means for adjusting the head cushion to any de-

40 sired angle; and to provide novel means whereby the members of the head cushion can be readily adjusted toward or from each other so as to provide a space between them or close them together according to the de-

45 sired position of the patient upon the table. Other minor objects and novel features of the invention will be hereinafter set forth.

I will explain the invention with reference to the accompanying drawings which 50 illustrate one practical chiropractic table embodying the invention and will enable others to fully understand the invention and adapt and use the same, but I do not consider the invention restricted to the arrangement of parts illustrated in the drawings and therefore refer to the appended claims

for summaries of the essentials of the invention, and the novel features of construction and novel combination of parts therein, for all of which protection is desired. 60

In said drawings;

Figure 1 is a side elevation of the complete table showing the table frame in lowered position in full lines, and indicating it partly raised in dotted lines. 65

Fig. 2 is a top plan view of Fig. 1, with the various cushions removed, but indicated in dotted lines.

Fig. 3^a is an enlarged longitudinal section through the left hand part of Fig. 2. 70

Fig. 3^b is an enlarged longitudinal section through the right hand part of Fig. 2.

Fig. 4 is a top plan view of the base section partly broken away to show the arrangement of the springs. 75

Fig. 5 is a section on the line 5—5 Fig. 3^a looking in the direction of the arrows.

Fig. 6 is a detail view of part of the leg cushion adjusting devices.

Fig. 7 is a detail view showing the head cushion adjusting devices.

Fig. 8 is a detail sectional view of part of the abdominal cushion adjusting devices.

As shown in the drawings the table comprises a lower supporting or base portion 85 and an upper adjustable table portion which as a whole is hingedly mounted upon the base so it can be swung from a substantially vertical to a horizontal position to facilitate the patient's getting upon or off of the table. 90

The base portion as shown comprises two opposite side castings 1 near one end thereof, the lower ends of which are attached to bars 1^a which extend approximately parallel and horizontally away from the members 1 and 95 are connected at their ends opposite the members 1 by casting 1^b. The castings 1 and 1^b are preferably provided with dependent portions which form four point supports for the base. The bars 1^a may be connected near the castings 1 by transverse tie casting 1^c (Fig. 4) and may be again connected near the castings 1^b by transverse member 1^d. 100

The table portion comprises a supporting 105 frame which consists of parallel tubes or rods 2 which are provided on their ends adjacent the castings 1^a with L-shaped castings each having a portion 2^a projecting above the rods 2 and hung on a transverse 110 rod or shaft 1^e, which is fastened to and between the upper ends of the castings 1 and

by which the table portion is hingedly supported on the base. Each L-shaped casting has a portion 2^b depending below the rods 2 (Figs. 1 and 3^b) and projecting beyond the same and connected by a transverse shaft 2^c. The other ends of the rods 2 are connected by a transverse casting 2^e which is provided with depending studs 2^f adapted to rest upon the top of the casting 1^b when the table section is in lowered position (Figs. 1 and 3^a). This casting 2^e also has a hook member 2^g which is adapted to engage a catch 3 mounted upon the casting 1^b to hold the frame in lowered position. This catch 3 may be mounted on a pin 3^a (Fig. 3^a) extending through the casting 1^b and normally held in position to engage the hook 2^g by means of a spring 3^b. The rod 3^a may have a head 3^c on its outer end (Fig. 1) by which it can be rocked by the hand or foot of the operator. The casting 1^b may be provided with beveled lugs 1^c on its upper side adapted to pass between the studs 2^f when the table section is lowered and properly align the table frame upon the base frame.

When the catch 3 is disengaged from the hook 2^g the table frame is swung upwardly on the shaft 1^c by spring devices herein-after referred to.

As shown (Figs. 2, 3^a, 3^b, 4) the rod 2^e is connected to helical contractile major springs 4 and intermediate supplemental springs 5. The springs 4 are connected at their rear ends to a wing nut 4^a which is engaged with a tubular adjusting bolt 4^b which passes through a central opening in the transverse member 1^d of the base (see Figs. 3^a and 4) and is securely held in position by a lock nut 4^c. The tension of the springs 4 can be regulated by adjusting the wing nut 4^a toward or from the member 1^d. The springs 4 should be of such strength and so adjusted that if the catch 3 is disengaged and no one is lying upon the table they will hold the table in elevated position as indicated in dotted lines in Fig. 1. Springs 4 also assist in cushioning the lowering of the table when the patient is being laid thereupon.

The rear ends of the supplemental springs 5 are connected to a collar 5^a (Figs. 4 and 3^a) loosely mounted on the inner end of a rod or pipe 5^b which extends through the tubular bolt 4^b. The collar 5^a is held confined to the rod in position to tension the spring by any suitable means such as indicated in Fig. 3^a. The rod 5^b is provided with 3 notches 5^c which are equally spaced apart lengthwise of the rod and are also arranged approximately 90 degrees apart around the rod (see Fig. 3^a). Any one of these notches may be engaged with a detent 5^d (Figs. 3^a and 5) which is retained in a casting 5^e screwed onto the bolt 4^b, the head

of this detent being adapted to project through an opening in the sleeve bolt into engagement with any one of the notches 5^c in the rod 5^b. The detent is preferably yieldingly pressed inwardly by means of a spring 5^f. By turning the rod 5^b the notch 5^c with which the detent is engaged can be moved out of engagement with the detent and then the springs 5 can pull the rod forward until another notch is engaged by the 75 detent.

The rod 5^b has an extension 5^h on its outer end which projects beyond the outer end of the adjusting bolt 4^b and extends through an opening or bearing in the end casting 1^b 80 and carries an adjusting hand wheel 5ⁱ attached thereto by which the rod 5^b can be turned so as to engage any desired notch 5^c therein with the detent 5^d. The said hand wheel 5ⁱ may be provided on its periphery 85 with indicating notches or marks corresponding in position to the several notches on the rod 5^b, so that by turning the wheel until the proper indicating mark is uppermost, the related notch 5^c in the rod 5^b will be 90 brought into engagement with the detent 5^d. The rod 5^h may carry a disk 5^o having peripheral recesses, corresponding in position to the marks on the wheel 5ⁱ, adapted to be engaged by a spring pressed detent or catch 95 5^p to hold rod 5^h in adjusted position—see Fig. 3^a.

The supplemental springs 5 are to assist in cushioning the lowering of the table with the patient thereon or lifting the table with 100 the patient thereon. When the table portion is in raised position these springs 5 become inert, and the point at which the springs 5 will become inert is determined in accordance with which notch 5^c is engaged 105 with the detent 5^d. When the table is raised and the springs 5 are inert the rod 5^b may be moved inwardly or outwardly so as to move the collar 5^a toward the detent by means of small springs 5^k connected to strap 5^l attached to the collar 5^a at one end and to the casting 1^b at the other end (see Fig. 3^a and 4).

The operating table has four cushion sections A, B, C and D. The section D is the 115 leg section and is slidably mounted on the table by any suitable means. As shown (Figs. 1 and 3^b) rods 6 are attached to its under side and slidably engage eyes 6^a on levers 6^b which are hinged on the rod 1^e to 120 which the table frame is hinged so that the section D may be adjusted longitudinally of the levers 6^b and consequently of the table normally by sliding it back and forth on the hinged members and may be fastened in adjusted position by means of a thumb screw 6^c attached to one of the hinge levers and engaging adjacent rod 6.

The cushion member D may also be adjusted at any desired angle relative to the 130

- table frame bars 2 by suitable means. As shown, a shaft 7 is journaled in bearings in the levers 6^b (Figs. 1, 2, 3^b and 6) and carries a pinion 7^a which meshes with a pinion 7^b on the upper end of a threaded screw 7^c which is journaled in a yoke 7^d hung on the shaft 7 and this screw engages a threaded opening in a yoke 7^e pivoted to and between the side members 2 of the cushion frame.
- 5 The shaft 7 can be operated by a handle 7^f and by rotating this shaft the screw is turned and the levers 6^b and cushion D thereby adjusted to any desired angle relative to the side members 2 of the table.
- 10 The abdominal cushion C (Figs. 1, 2 and 3^a) is attached to bars 8, which project beyond this cushion and are hinged on a transverse rod 8^a attached to castings 8^b slidably mounted on the side members 2 of the table.
- 15 and which castings are connected by the rod 8^a and also by a rod 8^c, so that they are held in proper position.
- The cushions C may be held in adjusted position either rigidly or yieldingly at the will of the operator by suitable means. As shown (Figs. 1 and 3^a) links 8^d are hung on a rod 8^p connected to the bars 8, and carry a rocking bar 8^e in which is journaled the upper end of a screw shaft 8^f operable by a handle 8^g. The lower end of shaft 8^f is journaled in a block 8^h swiveled in a bail 8ⁱ hung on the shaft 8^a. The hangers 8ⁱ have arms 8^j projecting toward the cushion C, and these arms are connected by springs 8^k to a traveling nut 8^m on shaft 8^f. By turning shaft 8^f to adjust the nut 8^m on such shaft, the tension of the springs 8^k can be varied, and the member C adjusted upwardly under more or less spring pressure of the springs 8^k.
- 20 To the nut 8^m is pivotally connected a tube 8^o which telescopes with one end of a rod 8^o, the other end of which is pivotally connected with the transverse rod 8^p (Figs. 2 and 3^a).
- 25 The members 8^d, 8^e, 8^o, 8^f, 8^g, 8ⁱ and 8^h form a four-point collapsible suspension frame connecting the cushion C with the bail 8ⁱ, but this four-point suspension frame is normally prevented from collapsing by the springs 8^k, whose resistance to collapse of this frame is regulable by varying the tension of the springs 8^k by adjusting the nut 8^m on the shaft 8^f. Thus the cushion C can be yieldingly supported by the springs 8^k under more or less tension.
- 30 In some cases it is desirable to have the cushion C rigidly supported. For this purpose I provide means whereby the collapsible spring controlled frame supporting the cushion C may be made rigid. As shown (Figs. 2 and 3^a) a latch member 8^t is connected to the shaft 8^p, and can be turned down over the rod 8° and the lower end of this latch 8^t when lowered (as shown in full lines in Fig. 3^a) engages the upper end
- 35 of tube 8°, and prevents parts 8° and 8° telescoping; and parts 8°, 8^t and 8° then form a rigid connection brace between the bar 8^h and rod 8^p and holds the cushion C rigidly in adjusted position.
- 40 The inclination of the cushion C, or its normal adjustment relative to the table frame 2 is regulable by a notched lever 8^r, pivoted on the rod 8^s and provided with a series of notches, which may be engaged with the ends of a transverse pin or rod 8^s, connected to the hangers 8 below the nut 8^m (Figs. 2 and 8). By varying the point of engagement of the notches in the lever 8^r with the pin or rod 8^s, cushion C can be adjusted at any desired inclination to the table 2, and may be yieldingly or rigidly supported in such adjusted position, as desired.
- 45 The chest cushion B is attached to arms 9, which are hinged on the shaft 8^a as indicated, the chest member overlying and resting upon the standard castings 8^b.
- 50 I prefer to form the head cushion A in two sections which are hinged side by side longitudinally of the table (Figs. 2 and 7). These are provided with ears 10 on their under side which slidably engage transverse rods 10^a mounted in a bail member 10^b hinged upon the rod 8 (Figs. 3^a and 7).
- 55 These head cushion sections may be adjusted toward and from each other by means of a lever 10^c pivoted to one side of the bail, as at 10^d, and having a T-head. One arm of this T-head is pivoted at 10^e to the under side of the left hand cushion section, and the other arm of this T-head is pivoted to one end of a link 10^f, which extends across the gap between the cushioned sections and is pivotally connected to the opposite cushion section. By turning lever 10^c on its pivot the cushion sections can be moved toward or away from each other according to the direction of movement of the lever 10^c.
- 60 The head cushion may be supported in various adjusted positions by means of a swingable supporting member 11 which is pivoted at one end to a casting 11^a on the rod 8^a, and its other end is pivoted to the outer end of the bail 10^b and is provided with an operating handle 11^b so that this bracket can be swung to the right or left. The portion of the member 11 adjacent the shaft 8^a is curved on an arc concentric with said shaft and is provided with a number 11^c of notches any one of which may be engaged with the tie rod 8^r between the castings 8^b. The member 11 is normally held in central position vertically beneath the head rest by means of springs 11^d (Figs. 3^a and 5) on opposite sides of the members and connected therewith and with the adjacent side castings 8^b.
- 65 When it is desired to adjust the angle of inclination of the head cushion this sup-

porting member 11 is swung laterally out of engagement with the rod 8^t and the head cushion adjusted by hand to the desired angle, then the member 11 is released and 5 is returned by springs 11^g to a central position beneath the head cushion and the proper notch in member 11 engaging the rod 8^t holds the head cushion in adjusted position.

To assist the patient in getting on and off

10 the table a foot rest is preferably provided. As shown (Figs. 1, 2 and 3^b) a foot rest 12 is connected to supports 12^a attached to rods 12^b, which telescope into the adjacent ends of the side tubes 2 of the table frame. This 15 foot rest may be adjusted toward or from the adjacent end of the cushion D, and held in adjusted position, by means of a bail 12^c pivotally connected to the supports 12^a and having an extension on its inner end provided with a series of notches any one of which may be engaged with a transverse rod 12^d attached to the side members 2, as indicated in Figs. 1 and 3^b.

20 A hand cushion 13 may be mounted on the table 2 beneath the head cushion A, so that the patient when lying face downward on the table may rest his hands on said cushion.

25 The base frame may be provided with a top plate 15 (Figs. 1, 3^b and 5) to cover the 30 spring mechanism, and protect them from dust or from being tampered with.

Operation.

35 When a patient is to be placed upon the table, the catch 3 is disengaged allowing the table frame to swing upwardly to approximately the position indicated in dotted lines in Fig. 1. The patient then steps upon the support 12 with his back or face to the cushions, then the table is lowered with the patient to the position shown in full lines in 40 Fig. 1.

45 The major springs 4 hold the table normally in raised position, when released by the catch, and cushion the lowering of the table. The springs 5 come into play as the table is lowered. By shifting the point of engagement of the rod 5^b with the detent 5^a the time when the springs 5 will come into 50 action and the strength thereof can be varied, so that the operator can cause these springs to offer more or less resistance to lowering of the table, and more or less help in raising the table with the patient thereon, 55 according to the weight of the patient.

60 The head cushion members may be readily adjusted together or spaced apart, according to whether the patient is to be face uppermost or face downward on the table.

65 The relative inclinations of the leg, abdominal, chest and head cushions can be adjusted by the operator according to the treatment the patient is to have, the abdominal cushion C can be locked rigidly in adjusted position by engaging the member 8^t

with tube 8°, as indicated in Figs. 1 and 3^a; or by turning this member 8^t to the position indicated in dotted lines in Fig. 3^a. The cushion C will be yieldingly supported by the four-point frame suspended by the 70 springs 8^k; the tension of these springs and resistance of the cushion C to depression being regulable by adjusting the nut 8^m.

75 The capability of the various parts for adjustment and the means for adjusting same, and the operation of the minor parts have all been hereinbefore clearly set forth. The advantages of the invention and utility of the table will be readily appreciated by chiropractors and physicians.

80 I claim:

1. In a table of the character specified; a base section; a table section pivoted thereon; major spring means connected to the table section; an adjustable tubular sleeve connected to the base, a member on said sleeve connected with the major spring means whereby the tension of the spring means can be adjusted; supplemental spring means connected with the table section; and means tel- 90 escoping said sleeve whereby the supplemental spring means may be adjusted so as to vary the point at which such springs will come into or go out of effective operation.

2. In a table of the character specified; a base section; a table section pivoted thereon; major spring means connecting the base and table sections; supplemental spring means connected with the table section; a longitudinally movable notched member connected 100 with the spring means to regulate the tension of the supplemental springs and vary the point at which such springs will come into or go out of effective operation; and means on the base engaging said notched member.

3. In a table of the character specified; a base section; a table section pivoted thereon; major spring means connected to the table section; an adjustable member connected to 110 the base and with the major spring means whereby the tension of the spring means can be adjusted; supplemental spring means connected with the table; a longitudinally movable notched rod connected with the base 115 whereby the supplemental spring means may be adjusted and a retainer on the base engaging the notches in said rod so as to vary the adjustment of the rod and the point at which such springs will come into or go out 120 of effective operation.

4. A table of the character specified; a base section; a table section pivoted thereon; major spring means connecting the base and table sections; supplemental spring means 125 connected with the table member; a rotatable longitudinally movable shaft connected with the spring means and having spaced notches around its periphery; and a retainer on the base adapted to engage the notched 130

shaft according to its rotative position to regulate the tension of the supplemental springs and vary the point at which such springs will come into or go out of effective 5 operation.

5. In apparatus of the character specified; a cushion hinged to the frame; a swingable member hingedly connected to the cushion and movable transversely of the cushion and 10 provided with notches adapted to engage a related device to hold the cushion in an angularly adjusted position.

6. In an apparatus as specified in claim 5; springs connected with opposite sides of the 15 swingable member to normally hold same in position beneath the cushion.

7. In an apparatus of the character specified; a hinged cushion supporting frame; a swingable member hingedly connected to the 20 frame and movable transversely of the cushion; and a relatively fixed rod; said swingable member having notches adapted to engage the rod to hold the cushion in an angularly adjusted position.

25 8. In an apparatus as specified in claim 7; springs connected with opposite sides of this swingable member to normally hold same in position beneath the cushion.

9. In apparatus of the character specified; 30 a cushion; a hinged bail supporting said cushion; a swingable member having one end connected in line with the hinge of the bail and its other end hingedly connected to the bail; the supporting member being 35 swingable transversely of the cushion and provided with notches in the portion adjacent the hinge of the cushion, and a device adapted to be engaged by one of these notches to hold the cushion in angularly adjusted position.

10. In an apparatus as specified in claim 9, springs connected with opposite sides of the swingable member to normally hold same in position beneath the cushion.

45 11. In apparatus of the character specified; a hinged cushion; a screw shaft swingably connected with the cushion; a pivotally mounted yoke having a threaded portion engaged by the screw shaft, and means for 50 rotating the screw shaft to angularly adjust the cushion substantially as described.

12. In apparatus of the character specified; a frame; a cushion; bars hinged to the frame and supporting the cushion; a slid able 55 connection between the cushion and the bars; a transverse shaft; a screw shaft swingably connected with the transverse shaft; a yoke pivotally mounted on the frame and having a threaded portion engaged by said screw 60 shaft; and gearing between the transverse shaft and screw shaft; whereby when the screw shaft is turned the cushion is angularly adjusted on the frame.

13. In a table of the character specified; 65 a supporting frame; a cushion hingedly con-

nected to the frame; a swinging member suspended from this cushion member; a second swinging member hinged on the supporting frame; a rotatable shaft supported by the said swinging members; a traveling 70 nut on said shaft, and spring means connecting said nut with one of said members substantially as described.

14. In combination with the mechanism set forth in claim 13; means for preventing 75 effective action of the springs; and means whereby the springs can be rendered effective when it is desired to have the spring yieldingly support the cushion member.

15. In combination with mechanism set 80 forth in claim 13; a member for rendering the spring ineffective; and means whereby this member can be rendered ineffective when it is desired to have the spring yieldingly support the cushion member.

16. In a table of the character specified; a supporting frame; a cushion hingedly connected to the frame; a swinging member suspended from the cushion; a second swinging member hinged on the supporting frame; 90 a rotatable shaft supported by the said swinging members; a traveling nut on said shaft; springs connecting said nut with one of said members; a telescopic brace member pivotally connected with the swinging members 95 and adapted to permit the springs to yieldingly support the cushion; and means whereby this brace member can be rendered rigid when it is desired to have the cushion unyielding.

100 17. In a table of the character specified; a supporting frame; a cushion hingedly connected to the frame; a swinging member suspended from the cushion; a second swinging member hinged on the supporting 105 frame; a rotatable shaft having bearings respectively supported by the said swinging members; a traveling nut on said shaft; springs connecting said nut with one of said members; a telescopic brace member pivotally connected with the swinging members and permitting the springs to yieldingly support the cushion; and means whereby this brace member can be rendered rigid 110 when it is desired to have the abdominal 115 member rigidly supported.

18. In apparatus of the character specified; a hinged cushion; links suspended from said cushion; a member hinged adjacent the hinge of the cushion; a screw shaft 120 having bearings respectively supported by said links and said hinged member; a traveling nut on said shaft; and springs connecting this nut with said hinged member.

19. In apparatus as set forth in claim 18; 125 means for rendering the springs ineffective.

20. In apparatus as set forth in claim 18; a member adapted to render the springs ineffective and thereby support the cushion rigidly; and means to render this member 130

ineffective and permit the springs to yieldingly support the cushion.

21. In apparatus of the character specified; a cushion; hinged bars supporting said cushion; links suspended from said bars; a bail hinged adjacent the hinge of the bars; a screw shaft; bearings therefor respectively supported on the links and on said swinging member; a traveling nut on said shaft; and springs connecting said nut with said bail.

22. In apparatus as set forth in claim 16; a member adapted to render the springs ineffective and thereby have the cushion rigidly supported; and means to render this member ineffective and permit the springs to yieldingly support the cushion.

23. In apparatus of the character specified, an abdominal member; hinged bars supporting said member; links suspended from said bars; a bail suspended from the frame adjacent the hinges of the bars thereto; a screw shaft; bearings therefor respectively pivotally supported by the links and by said swinging member; a traveling nut on said shaft; arms connected to said swinging member; springs connecting said nut with said arms; and disconnectible means connecting the links and member to render the springs effective or ineffective at will of the operator.

24. In apparatus as set forth in claim 16; a telescopic member comprising a tube and a rod respectively pivotally connected to the bail adjacent the bearing of the shaft there-

in and to the pivot of the links, and a locking member pivotally connected to the pivots of the bail adapted in one position to render the said collapsible member rigid.

25. In apparatus of the character specified in claim 18; a telescopic member comprising a tube and a rod respectively pivotally connected to the bail adjacent the bearing of the shaft therein and to the pivot of the links, and a locking member pivotally connected to the pivots of the bail adapted in one position to render the said collapsible member rigid.

26. In mechanism as set forth in claim 18; means adapted to vary the inclination of the cushion.

27. In mechanism as set forth in claim 18, an adjusting pivoted lever having notches adapted to engage the lower end of hinged member to vary the inclination of the abdominal cushion.

28. In mechanism as set forth in claim 21; an adjusting lever pivoted to the frame and having notches adapted to engage the lower end of the hinge member to vary the inclination of the cushion.

29. In mechanism as set forth in claim 23; an adjusting lever pivoted to the frame and having notches adapted to engage the lower end of the bail, to vary the inclination of the abdominal cushion.

In testimony that I claim the foregoing as my own, I affix my signature.

WILLIAM G. WILLIAMS.
